UNITED STATES PATENT OFFICE.

STEPHEN SZEKFU, OF ELLENSBURG, WASHINGTON, ASSIGNOR OF ONE-HALF TO
VICTOR E. MUNZ, OF ELLENSBURG, WASHINGTON.

HEEL FOR FOOT-GEAR.

1,106,989.

Specification of Letters Patent. Patented Aug. 11, 1914.

Application filed February 3, 1914. Serial No. 816,275.

To all whom it may concern:

Be it known that I, STEPHEN SZEKFU, a subject of the King of Hungary, residing at Ellensburg, in the county of Kittitas and State of Washington, have invented certain new and useful Improvements in Heels for Foot-Gear, of which the following is a specification, reference being had therein to the accompanying drawing.

10 This invention relates to heels for foot-gear, and has for its object to provide, in a manner as hereinafter set forth, a heel for boots, shoes and slippers to overcome the wearing off of the heel at the sides or at the 15 rear, or in other words to prevent what may be termed run-over heels when wearing a shoe provided with a heel in accordance with this invention.

20 A further object of the invention is to provide a heel, whether high or low, for foot-gear, in a manner as hereinafter set forth to provide a square foundation causing the wearer to step straight due to the fact that the heel sets firmly and squarely so that the 25 wearer cannot turn the ball of the foot thereby overcoming what may be termed run-over heels.

25 A further object of the invention is to provide a heel, whether high or low, for men's, ladies' and children's footgear, in a manner as hereinafter set forth, to prevent what is termed run-over heels and to further provide a heel for the purpose set forth which can be constructed of leather, paper, wood, metal 35 and rubber.

30 Further objects of the invention are to provide a heel for footgear, which is simple in its construction and arrangement, affording a square foundation to the wearer of the shoe, strong, durable, thoroughly efficient 40 in its use and inexpensive to manufacture.

45 With the foregoing and other objects in view, the invention consists of the novel construction, combination and arrangement of parts as hereinafter more specifically described and illustrated in the accompanying drawings, wherein is shown an embodiment 50 of the invention, but it is to be understood that changes, variations and modifications can be resorted to which come within the scope of the claims hereunto appended.

55 In the drawings wherein like reference characters denote corresponding parts throughout the several views—Figure 1 is a perspective view, Fig. 2 a rear elevation and

Fig. 3 an inverted plan of a heel for footgear in accordance with this invention, Fig. 4 is a perspective view, Fig. 5 an inverted plan and Fig. 6 a rear elevation of another form of a heel for footgear in accordance with 60 this invention.

Referring to Figs. 1, 2 and 3 of the drawings, the heel which is referred to generally by the reference character 7 is provided with a lower lift 8 having straight 65 side edges 9 and its rear edge 10 squared for a portion of its length and with the remaining portions slightly rounded as at 11, and merging into the rear ends of the side edges 9. The heel 7 has the rear thereof flat which 70 extends downwardly and forwardly at an inclination, and said flattened portion is indicated at 12. The sides of the heel 7 are flattened as at 13 and extend downwardly and 75 inwardly at an inclination.

The reference character 14 denotes the body portion of a slipper to which the heel 7 is attached. Setting up of the tread of the heel, the tread being the lower lift 8, in a manner as stated, sets up a square foundation for the wearer of the shoe and prevents the wearer from turning on the ball of the foot. By preventing the wearer from turning on the ball of the foot, it will cause the 80 wearer of the shoe to step straight thereby 85 overcoming the heel from being worn off in an irregular manner.

Referring to Figs. 4 to 6 of the drawings, 15 denotes a body portion of a shoe to which is attached a heel 16 having a lower lift 17 90 of rubber or other resilient material. The lift 17 is formed with straight side edges 18 and a rear edge 19 which is squared for a portion of its length, the remaining portions which are indicated by the reference character 20 are slightly rounded and merge in the rear ends of the edges 18. The rear of the heel 16 is flattened in a horizontal direction as at 21 and which extends downwardly and forwardly at an inclination. The squared portion of the rear edge 19 of the lift 17 forms a continuation of the portion 21. The side edges 18 of the lift 17 95 form a continuation of the sides of that part of the heel above said lift. By setting up the lift 17 in the manner as stated a square foundation is provided which will prevent the wearer of the shoe from turning on the ball of the foot and which will furthermore 100 cause the wearer to step straight preventing 105 110 115

the heel from being worn off in an irregular manner.

In Fig. 1 of the drawings, a high heel construction is illustrated, while in Fig. 2 a low heel construction is provided.

What I claim is:—

1. A heel for footgear including a body portion having the tread thereof formed with straight side edges and a rear edge 10 squared for a portion of its length, and the remaining portions of the rear edge being slightly rounded and terminating in the rear ends of the side edges.

2. A heel for footgear including a body 15 portion having the tread thereof formed

with straight side edges and a rear edge squared for a portion of its length, and the remaining portions of the rear edge being slightly rounded and terminating in the rear ends of the side edges, the rear portion of 20 said body being flattened in a horizontal direction and extending downwardly and forwardly at an inclination.

In testimony whereof I affix my signature in the presence of two witnesses.

STEPHEN SZEKFU.
